(57) **CLAIM**

The ornamental design for a molded surface of a concrete product, as shown and described.

DESCRIPTION

FIG. 1 is a perspective view of a molded surface of a concrete product according to our design;

FIG. 2 is another perspective view of the molded surface of a concrete product depicted in FIG. 1;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dot-dash broken lines depict the bounds of the claim. The broken lines in the drawings are included for the purpose of illustrating portions of the molded surface of a concrete product that form no part of the claimed design.
